UNITED STATES PATENT OFFICE.

PIERRE JOSEPH GRANDSIRE, OF DARNÉTAL, FRANCE.

APPARATUS FOR BLEACHING AND DYEING TEXTILES.

1,148,377.

Specification of Letters Patent.

Patented July 27, 1915.

Application filed July 21, 1913. Serial No. 780,236.

To all whom it may concern:

Be it known that I, PIERRE JOSEPH GRANDSIRE, a citizen of the French Republic, and resident at Darnétal, Seine Inferieure, 5 France, have invented certain new and useful Improvements in Apparatus for Bleaching and Dyeing Textiles.

The object of the invention is to provide convenient and efficient means for treating 10 textiles on the spindles as the same come from spinning frames, winding machines or the like.

The invention also relates to the details of construction and arrangement of parts 15 which will be hereinafter described and particularly pointed out in the claims.

In the drawing:—Figure 1 is a vertical section illustrating one form of my invention. Fig. 2 is a similar view of another 20 form of the invention. Fig. 3 is a view partially in section and elevation of a loaded bobbin and its mounting.

Referring to the drawings, B represents a receptacle having vertical side walls H, at 25 the upper ends of which is a horizontal flange h. In one end of the receptacle is an inlet tube h², and in the bottom of said receptacle are spindle receiving openings b, which receive tapered bushings b'. A cover 30 A, fits on the flange b, and when the apparatus is in use, said cover is bolted to the flange. In the cover are spindle receiving openings which receive tapered bushings, a', the latter being in vertical alinement 35 with the bushings b' in the receptacle B.

When in use, loaded spindles n, are mounted in the bushings a' and b', and the cover A, is clamped to the receptacle and bleaching or dyeing fluid is forced through 40 the tube h², which penetrates the textile material and is forced out of the receptacle at the ends of the spindles.

The construction shown in Fig. 2, comprises a receptacle B, having sides H, and 45 spindle receiving openings b. Formed with the receptacle B, at the bottom thereof is a channel C, which is open at one end as at c.

The cover A, in Fig. 2, is formed with spindle receiving openings a, and on the 50 upper side of said cover is formed a channel C', having an opening at one end c'.

The loaded spindles are mounted in the alined openings a—b, and the top is clamped to the receptacle and the bleaching or dyeing fluid is forced under pressure through 55 the tube h², and escapes around the ends of the spindles to the channels C and C'.

What I claim is:—

1. In an apparatus for treating textiles, the combination of a receptacle formed with 60 spindle receiving openings and an outlet opening, said receptacle having a flange at its upper edge, a cover plate fitted on top of the flanges, said cover plate having spindle receiving openings corresponding to and in 65 alinement with the spindle receiving openings in the receptacle, and tapered bushings in the spindle receiving openings whereby loaded spindles are inclosed to be treated and the treating fluid may escape 70 from the receptacle through the spindle receiving openings.

2. In an apparatus for treating textiles, the combination of a receptacle formed with 75 spindle receiving openings, and a channel under said openings, said channel being open at one end, the receptacle having an inlet opening, a cover plate fitted on the receptacle and formed with a plurality of spindle receiving openings and a channel above 80 said openings, the latter channel being open at one end.

3. In an apparatus for treating textiles, the combination of a receptacle formed with 85 alined spindle receiving openings in opposite walls, said receptacle having an inlet opening, and a channel formed adjacent one of the walls having the spindle receiving openings, said channel having an opening at one end, whereby loaded spindles 90 inclosed in the receptacle can be treated by fluid passed through said receptacle and channel.

In testimony whereof I have signed my name to this specification in the presence of 95 two subscribing witnesses.

PIERRE JOSEPH GRANDSIRE.
